United States Patent

Des. 236,694
Patented Sept. 9, 1975

236,694

DEVELOPER MIX STORAGE CONTAINER

Donald R. Avolio, Fairport, N.Y., assignor to Xerox
Corporation, Stamford, Conn.

Filed May 31, 1973, Ser. No. 365,809

Term of patent 14 years

Int. Cl. D9—03

U.S. Cl. D9—216

FIG. 1

FIG. 2

FIG. 3

FIG. 5

FIG. 4

FIG. 1 is a front perspective view of a developer mix storage container showing my new design;

FIG. 2 is a rear perspective view showing the side not seen in FIG. 1;

FIG. 3 is a side elevational view;

FIG. 4 is a front elevational view; and

FIG. 5 is a rear elevational view thereof.

I claim:

The ornamental design for a developer mix storage container, substantially as shown.
